United States Patent

Des. 239,442
Patented Apr. 6, 1976

239,442

ANCHOR

Paul Gunnar Wetterback, Stockholm, Sweden, assignor to
Arbman Development AB, Stockholm, Sweden

Filed Jan. 3, 1975, Ser. No. 538,480

Claims priority, application Sweden July 7, 1974

Term of patent 14 years

Int. Cl. D12—16

U.S. Cl. D12—215

FIG. 1

FIG. 2

FIG. 3

FIG. 1 is a perspective view of the anchor one of its blades being pivoted outwardly.

FIG. 2 is a plan view of the anchor in its storing position.

FIG. 3 is a side view of the anchor.

The anchor is symmetrical in all respects, and the sides not shown are identical to those that are shown.

I claim:

The ornamental design for an anchor, as shown and described.
